UNITED STATES PATENT OFFICE

153,983

DESIGN FOR A ROOF FINIAL

Max L. Rysdon, Sioux City, S. Dak.

Application June 19, 1947, Serial No. 139,809

Term of patent 14 years

(Cl. D68—1)

To all whom it may concern:

Be it known that I, Max L. Rysdon, a citizen of the United States and a resident of Sioux Falls, in the county of Minnehaha and State of South Dakota, have invented a certain new, original, and ornamental Design for a Roof Finial, of which the following is a specification, reference being had to the accompanying drawing, forming a part thereof.

Figure 1 is a side elevational view of the roof finial embodying my new design;

Figure 2 is a plan view thereof; and,

Figures 3 and 4 are rear and front end elevational views, respectively.

I claim:

The ornamental design for a roof finial, substantially as shown.

MAX L. RYSDON.
